Des. 234,011
Patented Dec. 24, 1974

234,011

ENGINE MANIFOLD

Walter John Warneford, 60-66 Nicholson St., Potts Point,
New South Wales, Australia

Filed Dec. 11, 1972, Ser. No. 314,183

Claims priority, application Australia Aug. 23, 1972

Term of patent 14 years

Int. Cl. D15—01

U.S. Cl. D77—1 A

FIG. 1 is an isometric view of an engine manifold showing my new design;

FIG. 2 is a bottom plan view;

FIG. 3 is a side elevational view;

FIG. 4 is a top plan view;

FIG. 5 is an end elevational view; and

FIG. 6 is a sectional view thereof taken on the line 6—6 in FIG. 3 and looking in the direction of the arrows.

I claim:

The ornamental design for an engine manifold, as shown.
